RAILWAY TRAFFIC CONTROLLING APPARATUS

Henry S. Young, Wilkinsburg, Pa., assignor to
The Union Switch & Signal Company, Swiss-
vale, Pa., a corporation of Pennsylvania

Application August 10, 1938, Serial No. 224,165

26 Claims. (Cl. 246—134)

My invention relates to railway traffic controlling apparatus, and more particularly to an interlocking control system for governing the movement of traffic through a track layout comprising 5
5 a plurality of track sections interconnected by track switches which may be variously arranged to form different traffic routes.

One object of my invention is the provision of an improved "all-relay" route interlocking system 10
10 for operating the switches and signals for the different traffic routes by means of levers and push buttons mounted on a track diagram in locations corresponding to the ends of the respective routes in which one or more of the track 15
15 switches may be operated as required and the signal governing traffic movements over the corresponding route may be cleared by the operation of a lever and push button associated with the entrance and exit ends, respectively, of the representation of that route on the track diagram. 20
20 A further object of my invention resides in the provision of apparatus for use in systems of this character which is particularly adapted to the control of a variety of different track layouts including those in which there are a plurality of 25
25 different routes extending between the same route ends. Other objects, purposes and features of my invention will be pointed out as the description proceeds.

30 My invention is an improvement upon those disclosed in the copending application for Railway traffic controlling apparatus, Serial No. 89,602, filed July 8, 1936, by R. A. McCann and H. S. Young; in the copending applications for 30
30 Interlocking control apparatus, Serial No. 14,868, filed April 5, 1935 by E. M. Allen and H. A. Thompson; and Serial No. 726,957, filed May 22, 1934 by L. E. Spray; and in the copending applications for Multiple control apparatus, Serial 40
40 No. 561,422, filed September 5, 1931 by L. E. Spray; and Serial No. 323,286, filed December 3, 1928, by L. E. Spray.

I shall describe three forms of apparatus embodying my invention, and shall then point out 45
45 the novel features thereof in claims.

Referring to the accompanying drawings, Figs. 1—A to 1—H, inclusive, taken together, illustrate one form of apparatus embodying my invention. In this form, Fig. 1—A illustrates a typical control panel containing the control levers and push buttons for controlling the apparatus of my invention and includes a track diagram which is a miniature representation of the track layout to be controlled. Fig. 1—D shows, in the upper portion, 50
50 a plan of the track layout to which the diagram

of Fig. 1—A corresponds, while Figs. 1—B to 1—H, inclusive, taken together, illustrate diagrammatically the circuits for a route interlocking system for controlling the switches and signals of Fig. 1—D in accordance with my invention. More 5
5 particularly, Fig. 1—B shows a route network including circuits by which route relays identified generally by the references N and R, for controlling the track switches, are controlled by the entrance levers E and the exit buttons X of Fig. 10
10—A, Fig. 1—C shows typical circuits for approach locking relays AS controlled by the signals. Fig. 1—D shows switch control and indication relays WR and WP. Fig. 1—E shows the switch locking relays LS which 15
15 together with the route relays of Fig. 1—B govern relays NWS and RWS for controlling the relays WR of Fig. 1—D, and also includes circuits for switch levers W by means of which the track switches may be operated individually. Fig. 1—F shows a signal network including circuits for controlling mechanisms G of the signals of Fig. 1—D. Fig. 1—G shows circuits for section locking relays ES and WS controlling the relays LS and also the route indicators K of Fig. 1—A, the circuits for the latter being shown in Fig. 1—H. Fig. 2 shows a modification of the route network of Fig. 1—B, illustrating how the invention may be applied to the different track layout shown in Fig. 2. Fig. 3 30
30 shows another modification of the route network of Fig. 1—B which illustrates one manner in which the invention may be applied to the track layout of Fig. 1—A when the intermediate signal 12 is omitted. 35
35

Similar reference characters refer to similar parts in each of the several views.

In order to simplify the description, I shall first explain the functions of the several parts of my apparatus, and shall then describe its operation under selected conditions in detail. 40
40

The track switches shown in the track plan of Fig. 1—D are identified by odd numbers 1, 3 and 5, and the way-side signals by the even numbers 2, 4, 6, 8, 10 and 12. The two switches of a crossover bear the same number but are distinguished by the suffixes A and B, respectively, on the track plan, and, similarly, in the case of multiple arm signals 4 and 8, the suffix A designates the top arm or high speed signal and C a slow speed signal. The single arm signals 2, 6, 10 and 12 are also slow speed signals. The high speed signals may be cleared only when the track sections in advance are unoccupied, while each slow speed 50
50 55

signal serves as a "call-on" signal which may be cleared to admit a train to an occupied block.

In the circuit plans, each relay or lever is identified by a letter or combination of letters pre-fixed by the designation of the switch, signal, or track section with which it is associated, and, in order to enable the circuits to be more readily understood, they are arranged in the written circuit form with similar circuits grouped together in the same view. In circuits of this form, the relay contacts are not necessarily shown adjacent the respective relays which operate them, and a contact is identified not only by a number but more particularly by showing the designation of the relay which operates it above the contact. Furthermore, instead of showing the local source of current for energizing the relays, I have shown only the terminals which are designated by the reference characters B and C, referring to the positive or supply terminal and to the negative or common return terminal, respectively, of the source.

To set up a route and clear the corresponding signal, signal 6 for example, the operator rotates the corresponding lever 6E associated with the route entrance on the diagram of Fig. 1-A to the right and then pushes the exit button 10X or 8X at the exit end of the representation of the desired route. Levers 2E and 12E are similar to 6E, while lever 10E governing traffic in the opposite direction is similar except that it is arranged to be moved to the left to clear signal 10. Lever 4E is a three-position lever which may be moved to the right to clear the high signal 4A or to the left to clear signal 4C when the proper exit button is operated, manual selection as to which of the two signals is to be cleared being effected in this manner. Lever 8E is similarly arranged to clear signal 8A or 8C when in its left or right-hand positions, respectively.

Each entrance lever E controls an entrance relay ER which when energized connects terminal C of the source to the adjacent end of each route circuit of Fig. 1-B which begins at the corresponding point, there being a route circuit in Fig. 1-B for each different route through the track layout. Each exit button X controls the pick-up circuit for an exit stick relay XS which when picked up connects terminal B to the end of each route circuit which ends at the corresponding point, to thereby complete the route circuit having its two ends at the points corresponding to the operated lever and push button and to energize a route relay for each switch of the route. The operation of levers 6E and 10X, for example, effects the energization of the route circuit which includes the route relays 3R and 5BN and the exit relay 10XS, which relays are held energized under the control of the entrance relay 6ER until lever 6E is manually restored to normal.

Referring now to Fig. 1-D, the track plan shown therein represents the track rails 1a and 1b of each of two main tracks connected by the crossovers 1 and 5, the lower track being also connected to a siding by a single switch 3. While a specific track layout is disclosed, it is to be understood that the apparatus of my invention is adapted to control other track layouts that may involve entirely different combinations of switches and signals, the present layout having been chosen to illustrate the principles of my invention in a simple manner. As indicated in the drawings, the tracks are divided into sections by insulated joints j, the detector sections of the

upper track which include the track switches bearing the references 1T and 5T while those for the lower track bear the references 3T and 7T. The adjacent approach sections of the two main tracks are designated 8T and 4T, respectively. Each track section is provided with the usual closed track circuit including a track battery 9 and a normally energized track relay, in accordance with standard practice, each track relay being identified by the reference character TR with a numerical prefix identifying the track section to which it corresponds.

Each track switch of Fig. 1-D is actuated by a power operated switch machine SM which, as herein disclosed, may be assumed to be of the type shown in the Zabel Patents Nos. 1,293,290 and 1,413,820. Each switch machine is provided with the usual motor having its operating circuits controlled by the contacts of the polarized switch control relay WR in the manner illustrated in the Willard Patent No. 1,380,452, as indicated diagrammatically by dotted line connections in the drawings, and it is to be understood that each switch or switches will be operated to normal, as shown, or to reverse, when the control relay WR is energized and its polar contacts are closed to the left or right, respectively. Each relay WR is controlled by a pair of interlocked stick relays NWS and RWS, as shown in Fig. 1-E, and these relays are controlled by the route relays N and R of Fig. 1-B when route control is used, or by the corresponding switch lever W when individual switch control is used. The switch stick relays NWS and RWS are also controlled by switch locking relay LS. The locking relays LS are controlled as shown in Fig. 1-E by the detector track relays TR of Fig. 1-D, the approach locking relays AS of Fig. 1-C, and the section locking relays ES and WS of Fig. 1-G.

Each switch machine is provided with the usual switch circuit controller, as disclosed in the Zabel patents hereinbefore referred to, for controlling a polarized switch indication relay WP, as indicated diagrammatically by dotted line connections in Fig. 1-D. For an understanding of the present invention it will suffice to point out that when both switch machines SM of the cross-over 1 or 5 are locked normal or reverse, the corresponding relay 1WP or 5WP will be energized and its polar contacts closed to the left or right, respectively, and that relay 3WP is similarly controlled by switch machine 3SM for the single switch 3.

Each switch indication relay WP is provided with a pair of repeating relays NWP and RWP each of which is energized only when the polarized relay WP is energized in a position corresponding to that of the associated switch control relay WR.

As will be hereinafter pointed out in detail, the locking relays LS together with the switch indication relays NWP and RWP control the route circuits of Fig. 1-B in such a manner that a route circuit can not be completed unless each switch of the route is either unlocked or already occupies a position in accordance with the route.

Fig. 1-F shows a signal network of interconnected circuits for controlling the signals of Fig. 1-D. Each signal has an operating mechanism, designated by the reference character G with identifying prefix in Fig. 1-F, and is controlled over a signal circuit which corresponds to the route which such signal governs and which includes contacts of the entrance relay ER, of the route relays N and R and the indication relays

NWP and RWP for the route. The signals may be of any desired type, but, as herein illustrated, it is to be understood that they are of the well-known searchlight type having mechanism G of the form disclosed in the E. J. Blake Reissue Patent No. 14,940 of August 31, 1920.

For simplicity each signal as illustrated is arranged to indicate either clear or stop, and the usual circuits for controlling each signal by the next signal in advance to provide a third indication have been omitted from the drawings since these are not essential to an understanding of the present invention.

Each signal mechanism or group of mechanisms G is provided with an approach locking stick relay such as the relays identified by the reference character AS in Fig. 1—C. To simplify the drawings only the circuits for the locking relays 12AS and 4AS are shown, but it is to be understood that the circuits for relays 2AS, 6AS and 10AS are similar to those for relay 12AS while the circuits for relay 8AS are similar to those for relay 4AS. These relays provide the usual time and approach locking of the switches and of opposing signals; thus when a signal assumes the stop position the energization of the associated relay AS is delayed for a predetermined time interval provided the signal is put to stop manually, this delay being nullified by the release of the corresponding track relay when the signal is automatically put to stop by a passing train. The approach locking relays AS control the section locking relays ES and WS by means of the circuits of Fig. 1—G, which relays provide the usual directional control of the switch locking and function so that when a train enters a route the locking of each switch ahead of the train will be maintained while the locking of each switch in the rear of the train will be released as soon as the corresponding track section is vacated.

The locking relays ES and WS also control the route indication lamps K located in the track diagram of Fig. 1—A. The arrangement is such that when a signal is cleared the corresponding approach locking relay AS is released, and this relay in turn deenergizes the section locking relay ES or WS for each section of the corresponding route. The section locking relays upon releasing complete circuits in Fig. 1—H in accordance with the position of the track switches so as to light selected indicator lamps K to display an illuminated representation of the established route on the track diagram. The lamps K remain lighted after the train enters the route and are extinguished successively when the section locking relays pick up as the corresponding track sections are vacated.

Since, as hereinbefore mentioned, the route network of Fig. 1—B corresponds in form to the actual track layout, it may occur that it provides a plurality of different circuit paths between the same route ends, certain of which do not correspond to available traffic routes, such as the one, for example, from signal 8 to signal 6 over switch 5A normal, and switches 1A, 1B and 3 reversed. One feature of my invention resides in the provision of means for preventing the energization of the route relays in such circuits as provided, for example, by including back contacts of relays 5ER and 6XS in the circuit path referred to. In other cases, there may actually be two available routes between the same route ends as, for example, route 8—4 from signal 8 to signal 4 over switch 5A normal and switches 1A and 1B reversed, or over switches 5A and 5B reversed and

switch 1B normal. The first of these is the preferred route because it does not interfere with train movements over the parallel route 6—10, and normally is the one that is rendered available in response to the operation of lever 8E and button 4X. However, the arrangement is such, as will hereinafter be explained in detail, that under certain conditions which prevent the establishment of the preferred route the alternative route over switches 5A and 5B reversed and switches 3 and 1B normal becomes established when lever 8E and button 4X are operated.

I shall now describe the operation of my apparatus under different assumed conditions. I shall first assume that the apparatus is in the condition shown in the drawings and that the operator desires to pass a train from section 5T, Fig. 1—D, over the preferred route 4—8 which extends over switches 1B and 1A reversed, past signal 12 and over switch 5A normal to section 8T.

To set up the preferred route 4—8 for a movement from left to right, the operator will first set up route 4—12 and then set up route 12—8, that is, he will first operate levers 4E to the left and will then press button 12X momentarily. This operation of lever 4E completes a circuit for relay 4CER which may be traced in Fig. 1—B from terminal B, contact 7 of lever 4E, relay 4CER, back contact 11 of relay 4XS to terminal C.

When button 12X is operated, a circuit is closed from terminal B, relay 12XS, contact 13, back contact 14 of relay 8EP to terminal C. Relay 12XS picks up, but the route relay 1R does not pick up at this time because, although terminal C is connected both to the left-hand terminal of its winding over front contact 15 of relay 4CER, it is also connected to the right-hand terminal of its winding over contacts 16, 13 and 14, so that there is no difference of potential between the two ends of the route circuit including relay 1R.

When button 12X is released to open contact 13, relay 1R picks up over the route circuit extending from terminal B, the winding and front contact 16 of relay 12XS, relay 1R, back contacts 17, 18, 19 and 20 of relays 1AN, 1EN, 2XS and 2ER, front contact 21 of relay 1LS, back contact 22 of relay 4XS, front contact 15 of relay 4CER to terminal C. Relay 1R will thus be held energized in series with relay 12XS as long as lever 4E is reversed, and by opening its back contacts 23, 24 and 117 will prevent the energization of the route circuits for the conflicting routes 2—12, 4—8 and 4—10. Relay 1R also closes contact 26, Fig. 1—E, completing a circuit from terminal B, contacts 25 and 26 of relays 1LS and 1R, relay 1RWS to terminal C. Relay 1RWS accordingly picks up, opening contact 27 to release relay 1NWS. Relay 1NWS, upon releasing, completes a stick circuit for relay 1RWS at its contact 28, and also completes a circuit from terminal B, front contact 29 of relay 1RWS, relay 1WR, back contact 30 of relay 1NWS to terminal C. Relay 1W therefore reverses and operates the switch machines 1ASM and 1BSM to reverse switches 1, 65 and also open its left-hand polar contact 31, Fig. 1—D, to release relay 1NWP.

Relay 1NWP, upon releasing, opens various front contacts in the circuits of Figs. 1—B, 1—E, 1—F, 1—G and 1—H.

When the switches 1 complete their movement and become locked reverse, the polarized switch indication relay 1WP, Fig. 1—D, becomes energized in the reverse direction, completing a circuit from terminal B over its neutral contact 75

32 and reverse polar contact 33, relay 1RWP, and reverse contact 34 of relay 1WR to terminal C.

Relay 1RWP therefore picks up and closes contacts in the circuits of Figs. 1—B, 1—E, 1—F and 1—H. In Fig. 1—E, the normal indication lamp 1NK for the switches 1 is extinguished and the reverse indication lamp 1RK becomes lighter, and in Fig. 1—F, a circuit is completed from terminal B, over front contacts 34, 35 and 36 of relays 12XS, 1RWP and 1R, back contact 37 of relay 4AER, front contact 38 of relay 4CER, the winding of the signal mechanism 4CG, back contact 39 of mechanism 4AG, and front contact 40 of relay 4CER to terminal C. Mechanism 4CG therefore becomes energized to cause signal 4C to indicate "proceed at slow speed".

Mechanism 4CG, upon becoming energized, opens contact 41, Fig. 1—C, in the circuit for relay 4AS, so that relay 4AS releases and opens contact 42, Fig. 1—E, to deenergize relay 1LS. Relays 1LS releases and opens its front contacts including contacts 25 and 43, Fig. 1—E, in the pick-up circuits for relays 1RWS and 1NWS to lock switches 1 reversed, and at its back contact 43 completes a circuit for lamp LK over front contacts 44 and 45 of the track relays 1TK and 1TK, lighting lamp LK to indicate to the operator the locked condition of switches 1.

Relay 4AS, upon releasing, also opens contact 46, Fig. 1—G, deenergizing relay 1ES. Relay 1ES releases and opens contacts 47 and 48, Fig. 1—G, in the circuits for relays 1ES and 3ES. Relay 1ES is thereby released, but relay 3ES does not release because contact 48 is now bridged by contact 49 of relay 1RWP. Relays 1ES and 1ES at their back contacts 50, 51 and 52, Fig. 1—H, complete circuits to light the route indicator lamps 1BK, 1RK and 1AK, respectively, in the track diagram of Fig. 1—A, thereby indicating the established route 4—12 on the diagram.

It will be noted that in Fig. 1—B the circuits for routes conflicting with route 4—12 are now open at contacts 53 and 54 of relay 1LS and contacts 55 and 56 of relay 1NWP but that the circuit for route 4—12 is now maintained closed at contact 57 of relay 1RWP although contact 21 of relay 1LS is open, so that signal 4—C will be held at clear until lever 4E is restored to normal.

I shall now assume that the operator moves lever 12E to the right and operates button 8X momentarily, to clear signal 12. The operation of button 8X completes a pick-up circuit from terminal B over back contacts 58 and 59 of relays 8AER and 8CER, front contact 60 of relay 8AS, relay 8XS, contact 61 of button 8X to terminal C. Relay 8XS picks up and when button 8X is released the route circuit for route 12—8 is energized from terminal B over contacts 58, 59 and 60, the winding and front contact 62 of relay 8XS, the winding of relay 5AN, back contact 63 of relay 5R, front contact 64 of relay 5LS, back contact 65 of relay 8EP, relay 12ER, right-hand contact 66 of lever 12E, back contacts 67 and 68 of relays 8CER and 8AER to terminal C. Relays 12ER and 5AN pick up, and relay 8XS is held energized over the circuit just traced, under the control of lever 12E. Relay 70 5AN opens contact 69 in the conflicting route circuit for relay 5R, and, in Fig. 1—E, closes contact 70 in the pick-up circuit for relay 5NWS. Relay 5WR therefore remains energized in the normal direction, and, in Fig. 1—F, a circuit 75 is completed from terminal B, front contact 71

of relay 8XS, back contacts 72 and 73 of relays 8CER and 8AER, front contacts 74, 75 and 76 of relays 5NWP, 5AN and 12ER, mechanism 12G, contact 77 of relay 12ER to terminal C. Mechanism 12G therefore becomes energized to clear signal 12.

Mechanism 12G upon becoming energized opens contact 78, Fig. 1—C, in the circuit for relay 12AS, releasing relay 12AS to open contact 79, Fig. 1—E, in the circuit for relay 5LS. Relay 5LS therefore releases and locks switches 5 normal, and, in Fig. 1—B, opens contacts in the route circuits for all routes over switches 5. Relay 5LS at its back contact 80, Fig. 1—E, completes the circuit for lamp 5LK. It will be noted that the opening of contact 84 in the route circuit for route 12—8 is without effect because that contact is bridged by contact 81 of relay 5NWP. Relay 12AS also opens contact 82, Fig. 1—G, releasing relay 5ES, which relay at its back contact 83, Fig. 1—H, completes circuits to light the route indicator lamps 5ANK and 5AK in the track diagram of Fig. 1—A, indicating to the operator that the portion 12—8 of the route 4—8 has been established.

I shall now assume that the approaching train passes signal 4C at clear and enters track section 7T. Track relay 7TR releases and at contact 88 opens the circuit for the stick repeater relay 7TS which releases. Relay 7TR at its back contact 45, Fig. 1—E, connects lamp 1LK to terminal C over the back contact 84 of a continuously operating interrupter relay CT. Lamp 1LK therefore will display a flashing indication, indicating the occupancy of section 7T or 1T, and the operator will restore lever 4E to normal, releasing relays 4CER, 1R and 12XS and consequently deenergizing mechanism 4CG to cause signal 4C to indicate stop and to close contact 41, Fig. 1—C, to reenergize relay 4AS. Relay 4AS picks up over a circuit from terminal B, contacts 133 and 41 of mechanisms 4AG and 4CG, back contact 150 of relay 7TR, normal contact 137 of a thermal relay 4TE, relay 4AS to terminal C. Relay 4AS upon picking up completes its stick circuit which extends to terminal B over contacts 133 and 41 and its own front contact 134. Switches 1 remain locked because the circuit for relay 1LS is now open at contact 85 of relay 7TS or at contact 86 of relay 1TR, Fig. 1—E. When the train vacates section 7T, relay 7TR picks up and by closing contact 87 reenergizes 1ES, which relay by opening contact 50 causes the route indicator lamp 1BK to be extinguished. Relay 7TR also closes contact 88, Fig. 1—D, reenergizing relay 7TS. When the train vacates section 1T relay 1TR picks up and completes the circuit for relay 1ES, Fig. 1—G, at its contact 89. Relay 1ES picks up and opens contacts 51 and 52 to extinguish the route indicator lamps 1RK and 1AK. Relay 1TR also closes contact 86, Fig. 1—E, reenergizing relay 1LS and thereby extinguishing lamp 1LK.

The various operations incidental to the movement of the train through the portion 12—8 of the route are similar to those just described, and it is believed they will be readily understood from the drawings without further detailed description.

The route circuits for train movements from right to left are somewhat different from those already described because there is no intermediate signal for that direction. To explain the operation of these circuits I shall assume that lever 8E is moved to the right and button 8X operated

momentarily, in order to establish route 8—4 and to clear signal 8—C. This results in the energization of relays 8CER and 4XS over circuits similar to those for relays 4CER and 8XS already traced. When relay 8CER picks up, a circuit is closed in Fig. 1—B from terminal B, back contact 58 of relay 8AER, front contact 59 of relay 8CER, back contact 90 of relay 5R, front contact 91 of relay 12AS, relay 8EP, back contacts 92 and 93 of relays 12ER and 12XS to terminal C. Relay 8EP therefore picks up and when button 4XS is released the circuit for route 8—4 over 1 reversed becomes energized from terminal B, back contacts 94 and 95 of relays 4AER and 4CER, front contact 96 of relay 4AS, the winding and front contact 22 of relay 4XS, front contact 21 of relay 1LS, back contacts 26, 19, 18 and 17 of relays 2ER, 2XS, 1BN and 1AN, relay 1R, back contact 16 of relay 12XS, front contacts 65 and 64 of relays 8EP and 5LS, back contact 63 of relay 5R, relay 5AN, back contact 62 of relay 8XS, front contact 97 of relay 8CER to terminal C. The route circuit for the alternative route 8—4 over 5 reversed does not become closed at this time because it includes the open back contact 113 of relay 8CER. Relays 1R and 5AN pick up and relay 4XS is held energized over the circuit just traced, switches 1 are reversed and switches 5 held normal as hereinbefore described, and when the route is established a circuit for mechanism 8CG is closed in Fig. 1—F from terminal B at contact 98 of relay 4XS, contacts 36, 37, 36, 35, 34, contact 99 of relay 8EP, contacts 76, 75, 74, back contact 73 of relay 8AER, front contact 12 of relay 8CER, the winding of mechanism 8CG, back contact 100 of mechanism 8AG, contact 101 of relay 8CER to terminal C.

Signal 8C therefore clears, releasing relay 8AS, which relay, as hereinbefore mentioned, is controlled in the same manner as relay 4AS of Fig. 1—C. Relay 8AS by opening contact 102, Fig. 1—G, releases relay 5WS, which relay by opening contacts 103 and 104 will selectively release relay 1WS or 3WS, dependent upon the position of switches 5. In this instance, since switches 5 are normal, relay 1WS releases and in turn, by opening contact 105, releases relay 7WS because switches 1 are reversed and contact 151 of relay 1NWS which normally bridges contact 105 is now open. Relay 5WS closes its back contact 106, Fig. 1—H, lighting the route indicator lamps 5AK and 5ANK. Relay 1WS at its back contact 107 completes a circuit to light lamp 1AK, while relay 7WS at contacts 108 and 109 completes circuits to light lamp 1RK and 1BK, thereby indicating the established route on the track diagram. Relay 8AS upon releasing also opens a contact 110, Fig. 1—E, releasing relay 5LS and relays 1WS and 7WS by opening contacts 111 and 112 release relay 1LS.

It will be readily apparent from the drawings that as the train enters route 8—4 and relay 8AS becomes reenergized, the route indicators will be extinguished and the locking for switches 5 and 1 will be released successively; indicators 5AK and 5ANK becoming extinguished and switches 5 released when section 5T is vacated, 1AK becoming extinguished when section 1T is vacated and 1RK and 1BK becoming extinguished and the locking for switches 1 released when section 7T is vacated.

I shall next assume that the operator is unable to establish route 8—4 as described, for the reason that signal 2 has been cleared to permit a train movement from left to right up to signal

12 at stop. The clearing of signal 2 will cause relay 1LS to release, and the route circuit traced for route 8—4 over 1 reversed will be open at contacts 21 and 57 of relays 1LS and 1RWP. The open contact 113 of relay 8CER in the circuit for the alternative route 8—4 over 5 reversed is now bridged by a branch circuit including contacts 114 and 115 of relays 12XS and 8EP, which is closed because relay 12XS has been picked up to clear signal 2. Back contact 115 of relay 8EP will be closed because contact 93 of relay 12XS in the circuit for relay 8EP is open and relay 8EP therefore does not pick up when relay 8CER becomes energized.

It follows that in this instance the energization of relay 8CER together with the momentary operation of button 4XS will complete a route circuit in Fig. 1—B from terminal B at contact 94 of relay 4AER over contacts 95 and 96, the winding and front contact 22 of relay 4XS, contact 56 of relay 1NWP, front contact 116 of relay 3LS, back contacts 117, 118, 119 and 120 of relays 1R, 3R, 6XS and 6ER, relays 1BN and 3N, front contact 114 of relay 12XS, back contacts 115, 121, 122 and 123 of relays 8EP, 8AER, 10XS and 10ER, front contact 124 of relay 5LS, back contacts 69 and 125 of relays 5AN and 5BN, relay 5R, back contact 62 of relay 8XS, front contact 97 of relay 8CER to terminal C. The energization of relays 1BN, 3N and 5R over the route circuit just traced will result in maintaining switches 1 and 3 normal and reversing switches 5. Furthermore, the route circuit just traced will remain energized even if signal 2 is now restored to stop and relay 12XS released, because contact 114 of that relay is bridged by contact 126 of relay 5R and the route circuit for the route 8—4 over 1 reversed is maintained open at back contact 18 of relay 1BN, and also at back contact 90 of relay 5R. The circuit previously traced in Fig. 1—F for mechanism 8CG is now open at contacts 36, 35, 99, 75 and 74 of relays 1R, 1RWP, 8EP, 5AN and 5NWP, but these contacts are now bridged by a branch circuit including corresponding front contacts 152 to 157, inclusive, of relays 1BN, 1NWP, 3N, 3NWP, 5R and 5RWP, as will be apparent from the drawings, so that signal 8C will clear.

Since switches 5 are reversed and switches 1 are normal, it will be apparent from Figs. 1—G and 1—H that when relay 8AS releases, relays 5WS, 3WS and 7WS will be released successively to light lamps 5AK, 5RK, 3NK, 1BNK, and 1BK to illuminate the representation of the established route on the track diagram.

The alternative route 8—4 over 5 reversed will also be established if the route buttons are operated when section 1T is occupied by a train moving over the switch 1A normal. In this instance the route circuit will be completed over a branch circuit bridging contact 113 of relay 8CER which includes front contact 127 of relay 1NWP and back contact 128 of relay 1TR, as shown in Fig. 1—B.

I shall next assume that the apparatus is in its normal condition, as shown, and that the operator wishes to clear the high speed signal 8A for a train movement over route 8—2. He will move lever 8E to the left and then operate button 2X momentarily. In this case, relays 8AER, 8EP, 5AN, 1AN and 2XS will become energized, switches 1 and 5 will be operated to normal, as shown, and signal 8A will clear. Signal 8A assumes the stop position automatically when a train passes it and enters section 5T, because the circuit for mechanism 8AG includes a front con-

tact 129 of the stick repeater relay 5TS controlled by track relay 5TR. Relay 5TS remains de-energized after the train vacates section 5T until lever 8E is restored to normal, for the reason that its pick-up circuit includes a back contact 130 of relay 8AER as shown in Fig. 1—D.

It may happen that the operator is unable to complete a route by operation of the route levers, due to failure of one or more of the track switches 10 to fully operate, as would be the case, for example, if there were an obstruction in a switch. In such case the operator would employ the individual lever W of Fig. 1—E to operate the switch back and forth to remove the obstruction or to restore 15 the switch to its original position.

To do this, it is necessary to first release the energized route relays by restoring the lever for the entrance end of the route to normal.

It will be clear from Fig. 1—E that the switch 20 stick relays NWS and RWS may be operated to actuate the corresponding relay WR, as required, by momentarily operating the corresponding switch lever W to the right or left, provided the switch locking relay LS for the switch is energized 25 at the time and the route relays are not energized, and each relay WR when so actuated will control the associated track switch to a corresponding position as already explained, the response of the track switch being indicated in the usual manner 30 by the lighting of lamp NK or RK. This portion of my apparatus is so arranged that the track switches will respond to the movement of a lever W only if such movement is made when the switch locking is released, and the switches will not be 35 operated automatically upon the release of the locking in the event a lever has been previously moved out of correspondence with the existing switch position and the switches have failed to respond because of their locked condition. That 40 is, the apparatus includes means for preventing the so-called "storage" of a switch operation. It will be apparent from Fig. 1—E that if lever 1W, for example, is moved to the left or right when the locking relay 1LS is deenergized due to contact 42 of relay 4AS being open, the subsequent 45 closing of contact 42 will not result in an operation of switches 1 because the circuit for relay 1LS will be open at the lever contact 131. Lever 1W must remain in its center position, as shown, 50 until relay 1LS picks up to establish its stick circuit over contact 132, and it follows, therefore, that any operation of lever 1W to left or right made while relay 1LS is deenergized is ineffective.

It will be apparent that the operator may set up 55 any desired route by the operation of the individual levers W and may then clear the corresponding signal by operating the proper entrance lever and exit button.

A further feature of my invention relates to 60 means for preventing a reversal of traffic direction under certain conditions. If signal 4C has been cleared as hereinbefore described to permit a train movement from section 4T to section 8T, relay 4AS will be deenergized and will not become 65 reenergized if lever 4G is restored to normal before the train enters section 7T until after the lapse of the usual time interval measured by the thermal relay 4TE of Fig. 1—C. In this case, when contact 41 of relay 4CG closes, contact 158 70 of relay 4TR in the pick-up circuit for relay 4AS is open, but a circuit is completed from terminal B over back contacts 133, 41, 134, and 135 of relays 4AG, 4CG, 4AS and 4TES through the heating element of the thermal relay 4TE to terminal 75 C. Relay 4TE will open its contact 137, and at the

end of a predetermined heating period, contact 136 of relay 4TE will close to pick up relay 4TES, which relay will then be held energized over its front contact 135 and will deenergize relay 4TE. At the end of a predetermined cooling period relay 4TE will close its contact 137 to complete a circuit from terminal B over contacts 133, 41, 138 and 137 of relays 4AG, 4CG, 4TES and 4TE, through relay 4AS to terminal C, so that relay 4AS will pick up and complete its stick circuit over contact 134 and deenergize relay 4TES. This prevents the operation of the track switches in the face of an approaching train in the usual manner, and, in addition, delays the reversal of the direction of the movement of track over the route 15 because contact 96 of relay 4AS in the pick-up circuit for relay 4XS remains open until the time interval measured by relay 4TE is completed.

Although I have in the foregoing traced but a few of the many possible operations of my apparatus, it is believed that the operation of setting up each of the remaining routes will be readily understood from the drawings without further explanation.

Referring now to Fig. 2, I have shown a different track layout including three routes between signals 4 and 8. For simplicity, all of the signals are shown as slow speed signals, but the route circuits in the lower portion of Fig. 2 are in other respects generally similar to those of Fig. 1—B. Of the three routes between signals 4 and 8, the one over switches 7 reversed has been chosen as the preferred route for movements from left to right and the one over switches 4 reversed as the preferred route for movements from right to left. Normally, all these three route circuits are open, the preferred routes mentioned being selected by the closing of contact 139 of relay 8XS or contact 140 of relay 4XS in response to the operation of the respective exit buttons 8X or 4X. In Fig. 2, relay 8XS controls two slow pick-up relays 8XP1 and 8XP2 which pick up successively at time spaced intervals when relay 8XS becomes energized, and relay 4XS similarly controls two slow pick-up relays 4XP1 and 4XP2, and since the operation in the two directions is similar, only that for movements from left to right will be described. I will first assume that lever 4E is moved to the right and that button 8X is operated momentarily. This normally will result in completing a route circuit for route 4—8 over 7 reversed, as will be readily understood in view of its similarity to the circuits of Fig. 1—B already described, this circuit including the relays 1BN, 5BN, 7R and 8XS. If now this preferred route 8—4 over 7 reversed fails to become established in response to the operation of button 8X or 4X for any reason, button 8X may be operated again and held closed for a time sufficient to cause relay 8XP1 to pick up.

Back contact 141 of relay 8XP1 will now open to prevent the subsequent closing of the preferred route circuit, and front contact 142 of relay 8XP1 will close to prepare the circuit for the alternative route 8—4 over switches 5 reversed. If this alternative route circuit fails to become energized upon the release of button 8X after relay 8XP1 is picked up, the button may be closed again and held closed until relay 8XP2 picks up. Back contact 143 of relay 8XP2 will open to prevent the closing of the circuit for route 4—8 over switches 5 reversed, and contact 144 of relay 8XP2 will close to prepare the circuit for the second alternative route 8—4 over switches 1 reversed.

It will be clear that since in each case the route circuit does not become energized until the exit button is released, the operator may select manually any one of the three routes by a single operation of the exit button, the particular route selected being dependent solely upon the length of time the button is held in its operated position. It is obvious that suitable indication means controlled by the relays XP may be provided to indicate which of these relays is picked up in order to inform the operator as to which route will be completed upon the release of the button at any time during the operation of these relays.

In Fig. 3 I have shown the same layout as that controlled by the first form of the apparatus except that the intermediate signal 12 is omitted and all the signals are shown as slow speed signals for simplicity. It will be remembered that in Fig. 1—B there are in some instances multiple circuit paths between the same route circuit ends, for example, from terminal B at back contact 58 of relay 8AER one circuit may be traced through relays 8XS, 5R and 3R, and another through relays 8XS, 5AN, 1R, 1BN, 3N and 3R to terminal C at contact 145 of relay 6ER. The closing of the last-mentioned circuit, which obviously does not correspond to any available route, is avoided, when relay 6XS or 6ER is operated, because it includes back contacts 119 and 120 of these relays. Similar contacts are included in each circuit of a corresponding nature in Fig. 1—B. In Fig. 3, the necessity for these additional checking contacts is avoided by arranging the circuits so that the flow of current is always in the same direction, that is, as shown, from terminal B at the left to terminal C at the right, and by including asymmetric units, preferably of the copper oxide rectifier type, in certain of the circuits so as to permit the flow of current only in the desired direction. Thus for example, in Fig. 3, current may flow from terminal B at contact 146 of relay 6XS through relays 3R, 5R and 8XS to terminal C, while the flow of current through the branch around relay 5R including relays 3N, 1BN, 1R and 5AN is blocked by the asymmetric unit 147.

It will be evident from the drawings that the three units 147, 148 and 149 in Fig. 3 prevent the energization of any undesired circuit path of the type described in the layout.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In an interlocking control system, a track layout including a plurality of track switches which may be arranged to form different traffic routes, a normal and a reverse control relay and a locking relay for each switch, manually operable contact means for the ends of said routes, a route network including a route circuit for each route, each such circuit including the normal or reverse control relay and a front contact of the locking relay for each switch of such route, means for energizing each route circuit to pick up the normal or reverse control relays as required to establish such route when the contact means for its two ends are operated, switch indication relays indicating the positions of the track switches, means comprising contacts of said indication relays for bridging the locking relay front contacts

contacts in the route circuit for each route only when the corresponding switches occupy the positions required for such route, and means deenergizing the locking relay for each switch of a route when such route is fully established to isolate the energized route circuit from all conflicting route circuits.

2. In an interlocking control system, a track layout including a plurality of track switches which may be arranged to form different traffic routes, a normal and a reverse control relay and a locking relay for each switch, manually operable contact means for the ends of said routes, a route network including a route circuit for each route, each such circuit including the normal or reverse control relay and a front contact of the locking relay for each switch of such route, means for energizing each route circuit to pick up the normal or reverse control relays as required to establish such route when the contact means for its two ends are operated, switch indication relays indicating the positions of the track switches, means comprising contacts of said indication relays for bridging the locking relay front contacts in the route circuit for each route only when the corresponding switches occupy the positions required for such route, signals for governing traffic movements over said routes, means for clearing the signal governing traffic movements over that route having its route circuit energized when such route is fully established, and means deenergizing the locking relay for each switch of a route when the signal governing traffic movements over such route is cleared.

3. In an interlocking control system, a track layout including a plurality of track switches which may be arranged to form different traffic routes, a normal and a reverse control relay and a locking relay for each switch, manually operable contact means for the ends of said routes, a route network including a route circuit for each route, each such circuit including the normal or reverse control relay and a front contact of the locking relay for each switch of such route, means for energizing each route circuit to pick up the normal or reverse control relays as required to establish such route when the contact means for its two ends are operated, switch indication relays indicating the positions of the track switches, means comprising contacts of said indication relays for bridging the locking relay front contacts in the route circuit for each route only when the corresponding switches occupy the positions required for such route, signals for governing traffic movements over said routes, means for clearing the signal governing traffic movements over that route having its route circuit energized when such route is fully established, means deenergizing the locking relay for each switch of a route when the signal governing traffic movements over such route is cleared, and means reenergizing each locking relay when a train governed by such signal has passed fully over the corresponding track switch.

4. In an interlocking control system, a track layout including a plurality of track switches which may be arranged to form different traffic routes, signals for governing traffic movements over said routes, a normal and a reverse control relay for controlling and a locking relay for locking each switch, normal and reverse indication contacts controlled by each switch and closed only when the switch occupies the corresponding normal or reverse position, a route network including a route circuit for each route each such circuit including the normal or reverse control relay for

each switch of the route and in series therewith the indication contact for each switch of the route which is closed when such switch occupies a position in accordance with the route and in multiple with such contact, a contact of the locking relay for the corresponding switch which is closed when the switch is not locked by such relay, and means for energizing each route circuit to pick up the normal or reverse control relays as required to establish the corresponding route and to clear the signal for such route when fully established.

5. In an interlocking control system, a track layout including a plurality of track switches forming different traffic routes certain of which conflict with others, a route network including a route circuit for each route, a manually operable relay for each route end, means responsive to the energization of the manually operable relays for the opposite ends of a route to energize the route circuit for said route, means comprising a back contact of one of said relays included in the route circuit for a route conflicting with the route governed by said relays for preventing the energization of the route circuit for such conflicting route when said one relay is energized, and means controlled by the energized route circuit for operating the track switches as required to establish the corresponding route.

6. In an interlocking control system, a track layout including a plurality of track switches which may be arranged to form a plurality of traffic routes said layout including two alternative routes between the same route ends, a route network corresponding to said track layout including a route circuit for each route, one or more of such circuits extending from each route end at one end of said network to each route end at the other end thereof, a manually operable relay for each route end, means responsive to the energization of the manually operable relays for the opposite ends of a route to energize the route circuit for said route, means including a back contact of the relay for one of the common ends of said two alternative routes for preventing the energization of more than one of the route circuits for said alternative routes when the relays for the opposite ends of such routes are energized, and means controlled by each route circuit when energized for operating the track switches as required to establish the corresponding route.

7. In an interlocking control system, a track layout including a plurality of track switches forming different traffic routes, a control lever and a push button for each route end, an entrance relay and an exit relay for each route end, a circuit for each entrance relay closed when the control lever for the same route end is in its operated position and the exit relay for that route end is deenergized, a pick-up circuit for each exit relay closed when the push button for the same route end is operated and the entrance relay for that route end is deenergized, a normal and a reverse control relay for each track switch, a route network including a route circuit for each direction for each route through the track layout each such route circuit including a front contact of the entrance relay for one end of the route, the winding of the normal or reverse control relay for each switch of the route, and the winding and front contact of the exit relay for the other end of the route, and a source of current for energizing each route circuit rendered effective when the pick-up circuit for the exit relay for the corresponding route is opened to actuate the normal

and reverse control relays as required to establish such route.

8. In an interlocking control system, a track layout including a plurality of track switches which may be arranged to form different traffic routes said layout including two alternative routes between the same route ends, a normal and reverse control relay for each switch, a route network including a route circuit for each route each such circuit including in series the normal or reverse control relay for each switch of the route and contacts which open when route circuits for conflicting routes are energized, manually operable means for each route end in said layout, means responsive to the operation of the manually operable means for the two ends of a route to energize the corresponding route circuit to pick up the normal and reverse control relays as required to establish such route, and selecting means comprising contacts included in the route circuits for said two alternative routes and effective to prevent the energization of one but not of the other of said two alternative routes in response to the operation of the manually operable means for the opposite ends of such routes unless a route circuit conflicting with said other alternative route but not with said one route is energized.

9. In an interlocking control system, a track layout including a plurality of track switches which may be arranged to form different traffic routes said layout including two alternative routes between the same route ends, a normal and reverse control relay for each switch, a route network including a route circuit for each route each such circuit including in series the normal or reverse control relay for each switch of the route, manually operable means for each route end in said layout, means responsive to the operation of the manually operable means for the two ends of a route to energize the corresponding route circuit to pick up the normal and reverse control relays as required to establish such route, contact means included in the route circuits for said two alternative routes and normally effective to prevent the energization of one but not of the other, and means for operating said contact means automatically to permit the energization of the route circuit for said one alternative route when a train occupies a route conflicting with said other alternative route but not with said one alternative route.

10. In an interlocking control system, a track layout including a track switch, a locking relay effective when deenergized to prevent the operation of the track switch, a normal and a reverse switch control relay, normal and reverse indication contacts controlled by the track switch to indicate its position, means effective when the normal or reverse switch control relay is energized to operate the switch to a corresponding position and to maintain it in such position as long as such control relay remains energized, means effective only if a control relay is energized and the corresponding normal or reverse indication contact is closed to deenergize said locking relay, and energizing circuits for the normal and reverse control relays each including the corresponding normal or reverse indication contact and in multiple therewith a front contact of said locking relay.

11. In an interlocking control system, a track layout including a track switch, a locking relay effective when deenergized to prevent the operation of the track switch, a signal for governing

- traffic movements over the switch, normal and reverse indication contacts controlled by the track switch to indicate its position, means effective when the normal or reverse control relay is energized to operate the switch to a corresponding position and to maintain it in such position as long as such control relay remains energized, means effective only when a control relay is energized and the corresponding normal or reverse indication contact is closed to clear said signal, means controlled by said signal when clear to deenergize said locking relay, and energizing circuits for the normal and reverse control relays each including the corresponding normal or reverse indication contact and in multiple therewith a front contact of said locking relay.
12. In an interlocking control system, a track layout including a plurality of track switches, which may be arranged to form different traffic routes, signals at the ends of said routes for governing traffic movements over said routes, an approach locking relay for each signal, means deenergizing each approach locking relay when the corresponding signal is cleared and for a predetermined time interval after the signal is restored to stop, manually operable entrance and exit relays for each route end, a circuit for each entrance relay including a manually operable contact, a circuit for each exit relay including a manually operable contact and a front contact of the approach locking relay for the same route end, means effective when the entrance and exit relays for the two ends of a route are both energized to operate the track switches as required to establish such route, and a circuit for clearing the signal for such route closed when said route is established by the operation of the track switches and including front contacts of said energized entrance and exit relays.
13. In an interlocking control system, a track layout including a plurality of track switches which may be arranged to form different traffic routes, signals at the ends of said routes for governing the movement of traffic over said routes, including a high speed signal and a slow speed signal at one route end, a control lever and a push button for each route end, an entrance relay for each signal, an exit relay for each route end, means for clearing each signal except said slow speed signal when the control lever for the same route end is moved to a given operative position and the push button at the exit end of a route which such signal governs is operated, and means for clearing said slow speed signal when the control lever at the same route end is moved to a different operative position and the push button at the exit end of a route which such signal governs is operated.
14. In combination with a section of railway track including a track switch, a track diagram arranged to represent said section, three lamps mounted on said diagram including one in each branch track on the trailing side of the switch and one in the single track on the facing side of the switch, a normal and a reverse indication relay controlled by the track switch and energized only when the track switch is in a corresponding position, a locking relay which when deenergized prevents operation of the track switch, a circuit controlled by a back contact of said locking relay for lighting said single track lamp, circuits controlled by a back contact of said locking relay and by front contacts of said normal and reverse indication relays respectively for selectively lighting one branch lamp or the other in accordance with the position of the track switch, control means for establishing traffic routes over said track switch, and means releasing said locking relay when a traffic route over said track switch is established.
15. In an interlocking system for railroads, a track layout comprising a plurality of track sections interconnected by track switches to form different traffic routes, a track diagram arranged to represent said layout, a plurality of route indication lamps mounted in the tracks of said diagram, a normal and a reverse indication relay controlled by each track switch and energized only when the track switch is in a corresponding position, a locking relay for each direction for each track section, control means for establishing different traffic routes through said track layout, means effective when any traffic route is established in either direction for releasing the locking relay for the same direction for the track section at the entrance to said route, means selectively controlled by the switch indication relays for selectively releasing the locking relays for the same direction for each of the remaining sections of said route, each in response to the release of the locking relay for the preceding section, circuits controlled by back contacts of said locking relays for lighting those lamps in corresponding sections of the track diagram located in the single track portions adjacent the facing side of a switch, and circuits controlled by back contacts of said locking relays and by front contacts of said normal and reverse indication relays respectively for selectively lighting these lamps in the corresponding sections of the track diagram located on the track diagram adjacent the trailing side of a switch each in accordance with the position of the corresponding track switch.
16. In combination with a detector section of railway track including a track switch, a track relay for said detector section, a manually operable circuit controller having a normal and a reverse position and a center position, a locking relay, a pick-up circuit for said locking relay controlled by a front contact of said track relay and a contact closed only when said circuit controller occupies its center position, a stick circuit for said locking relay controlled by said track relay for maintaining the locking relay energized when said circuit controller occupies its normal or reverse position, and circuits for operating the track switch to its normal or reverse position including front contacts of said locking relay and contacts closed when said circuit controller is moved to the corresponding normal or reverse position.
17. In an interlocking system for railroads, a track layout including a plurality of track switches which may be arranged to form different traffic routes, said layout including a plurality of alternative routes between the same route ends, manually operable contact means for the ends of said routes, a route circuit for each route, timing means controlled by the contact means for one end of said alternative routes for selecting the route circuit for a particular one of said alternative routes for energization depending upon the length of time said contact means is maintained in its operated condition, means responsive to the operation of the contact means for the two ends of a route to energize the corresponding route circuit, and means controlled by each route circuit when energized to operate the track switches as required to establish the corresponding route.

18. In an interlocking control system, a track layout including parallel tracks connected by track switches which are manually controllable to form different traffic routes a locking relay for each switch controlled by traffic conditions, a route network corresponding to said track layout and comprising a plurality of interconnected circuits including a route circuit for each traffic route through said layout, manually operable contact means for the ends of the routes, means responsive to the operation of the contact means for the two ends of a route to energize the corresponding route circuit, provided either that the locking relay for each switch of the route is energized or that such switch occupies the position required for the route, means comprising asymmetric units included in portions of said route circuits to prevent the diversion of current from an energized route circuit to interconnected portions of other route circuits, and means controlled by each route circuit when energized to operate the track switches as required to establish the corresponding route.

19. In combination with a railway track switch, a locking relay which when deenergized prevents operation of the switch, a control lever having an inactive position and a normal and a reverse control position, a pick-up circuit for said locking relay controlled by traffic conditions and including a contact closed by said lever in its inactive position, a stick circuit for said locking relay independent of said lever contact, and means for operating the track switch to normal or reverse effective when the lever is moved to its corresponding control position provided said locking relay is energized.

20. In an interlocking system, a track layout comprising a plurality of track sections interconnected by track switches to form different traffic routes, a normal control relay and a reverse control relay for each switch, a route network comprising a plurality of interconnected circuits each corresponding to one of said routes and each of which includes in series the winding of the normal or reverse control relay for each switch in the corresponding route, a manually operable relay for each route end at each end of said network, means responsive to the successive energization of the manually operable relays at the opposite ends of a route to energize the network circuit for said route thereby operating the switch control relays to establish said route, and means including a back contact of one of said manually operable relays for opening the network circuit for a conflicting route.

21. In combination, a track layout including a plurality of track switches, a locking relay for each switch effective when deenergized to prevent operation of the switch, a signal for governing the movement of traffic over a particular route through said track layout, a route relay for each switch of said route effective when energized to operate that switch to a position in accordance with said route, a route circuit for said route including all said route relays in series and also including a front contact of the locking relay for each switch of the route, each said front contact being bridged by a contact controlled by the corresponding switch and closed only when the switch is in a position in accordance with said route, means controlled over said route circuit for clearing said signal when said route is fully established, and means controlled by the signal when clear for releasing the locking relay for each switch of said route.

22. In combination, a track layout including a plurality of track switches, a locking relay for each switch effective when deenergized to prevent operation of the switch, a manually operable contact for each track at each end of the layout, a route circuit for each traffic route through the track layout including relay means which when energized is effective to operate each switch of the route to a position in accordance with that route, means including the manually operable contacts for the two ends of each route for energizing the corresponding route circuit, means preventing the energization of a route circuit when such two contacts are closed unless each locking relay for a switch of the route is energized or the switch which such locking relay controls is already in the proper position to establish said route, and means for deenergizing the locking relay for each switch of a route when such route is fully established.

23. In combination, a track layout including a plurality of track switches, a locking relay for each switch effective when deenergized to prevent operation of the switch, a manually operable contact for each track at each end of the layout, a route circuit for each traffic route through the track layout including relay means which when energized is effective to operate each switch of the route to a position in accordance with that route, and which also includes a front contact of the locking relay for each switch of the route, means including the manually operable contacts for the two ends of each route for energizing the corresponding route circuit, and means for deenergizing the locking relay for each switch of a route when such route is fully established.

24. In combination, a track layout including a plurality of power operated track switches, a control relay for each switch for controlling its operation, a locking relay for each switch effective when deenergized to prevent the operation of the control relay for that switch, a manually operable contact for each track for each end of the track layout, a route circuit for each traffic route through the track layout including relay means for operating the control relay for each switch of the route to establish that route, which circuit also includes a front contact of the locking relay for each switch of the route, means including the manually operable contacts for the two ends of each route for energizing the corresponding route circuit, and means for deenergizing the locking relay for each switch of a route when such route is fully established.

25. In combination, a track layout including a plurality of power operated track switches, a control relay for each switch for controlling its operation, a locking relay for each switch effective when deenergized to prevent the operation of the control relay for that switch, a manually operable contact for each track for each end of the track layout, a route circuit for each traffic route through the track layout including relay means for operating the control relay for each switch of the route to establish that route, which circuit also includes a front contact of the locking relay for each switch of the route bridged by a contact closed only when the switch occupies a position in accordance with that route, means including the manually operable contact for the two ends of each route for energizing the corresponding route circuit, and means for deenergizing the locking relay for each switch of the route when such route is fully established.

26. In an interlocking system for railroads, a

track layout including a plurality of track switches arranged to form a plurality of different traffic routes including two alternate routes between the same points at the ends of the track layout comprising a preferred route and a secondary route, a plurality of signals for governing traffic movements over said routes, a manually operable contact for each route end and at each end of the layout, a route circuit for each route, means responsive to the joint operation of the contacts for the opposite ends of a route to energize the route circuit for that route, said means being normally effective in the case of said alter- native routes to energize the route circuit for said preferred route only, means controlled by each route circuit when energized to operate one or more of the track switches as required to establish the route and to clear the signal for that route, and time controlled means rendered effective when the contacts at the ends of said alternate routes are operated if the preferred route does not become established within a predetermined time to open the route circuit for that route and to close the route circuit for said secondary route.

HENRY S. YOUNG.

DISCLAIMER

2,179,462.—*Henry S. Young, Wilkinsburg, Pa.* RAILWAY TRAFFIC CONTROLLING APPARATUS. Patent dated November 7, 1939. Disclaimer filed June 19, 1941, by the assignee, *The Union Switch and Signal Company*.

Hereby disclaims the subject matter of claims 8 and 9.
